DECK LID SUPPORT

George N. Harden, Marion, Ohio, assignor to
Ternstedt Manufacturing Company, Detroit,
Mich., a corporation of Michigan

Application May 2, 1938, Serial No. 205,449

2 Claims. (Cl. 217—60)

This invention relates to a deck lid support and more particularly to a deck lid support for the rear deck lid of an automotive vehicle.

It is the object of this invention to produce a strong and simple deck lid support provided with an automatic latching arrangement.

In the drawings:

Fig. 1 is a fragmentary side elevation of an automotive vehicle showing the deck lid support assembled to the deck and deck lid with the deck lid raised.

Fig. 2 is a side elevation of the deck lid support in the position the parts assume when the lid is lowered.

Fig. 3 is a partial section and elevation along the line 3—3 of Fig. 2.

Fig. 4 is a section along the line 4—4 of Fig. 3.

Fig. 5 is a detail of the latching pin.

Fig. 6 is a sectional view indicating the travel of the pin during the raising, supporting and lowering of the lid and lid support.

Fig. 7 is an inside elevation of one of the two stampings forming the outer lid support member.

Referring more particularly to the drawings there is shown an automobile having the deck lid 1 hinged at 2 to the rear deck 3 of the vehicle. The lid 1 is shown in raised position, Fig. 1, and supported by a lid support comprising an inner member 4 which has a telescopic sliding connection with an outer member 5. The member 4 is pivoted as at 6 to bracket 7 which is secured to the lid 1 and the member 5 is pivotally connected as at 8 to a bracket 9 which is secured to the deck 3. The member 4 takes the form of a solid steel bar provided adjacent one end with the transverse slot 10 which is arranged to receive the pin 11 and to guide the same during the operation of the lid support latch. The pin 11 is provided with a bore 12 in which is mounted the plunger 13 and the coil spring 14. The member 4 is arranged to slide and telescope within the member 5.

The member 5 comprises a pair of matched, symmetrical stampings 15 and 16 of channel cross section. The stamping 15 is provided with a plurality of lugs 17 which pass through openings 18 in the stamping 16 and are turned over to secure the two stampings together.

The lid support is provided with automatic latching and unlatching mechanism which includes the pin 11 and slot 10 in the member 4 above described. Since the pin 11 in performing its automatic latching and unlatching function must be actuated and guided, to this end it is proposed to form the guideway and the cam for actuating the pin 11 directly in the stampings 15

and 16. As shown, each stamping is provided with an elongated groove 20 extending along and parallel to the right-hand longitudinal side edges of the stampings 15 and 16 as viewed in Fig. 2. The groove 20, which is stamped directly in each of the stampings 15 and 16, communicates with the circuitous groove 21 about island 22. Thus, as viewed in Fig. 2, grooves 20 and 21 in stamping 16 are pressed outwardly of the stamping 16 toward the reader whereas grooves 20 and 21 in stamping 15 are pressed outwardly of stamping 15 away from the reader. The grooves 20 and 21 are stamped simultaneously and directly into stamping 15 and simultaneously and directly into stamping 16. Thus the stampings 15 and 16 with the stamped in grooves 20 and 21 are symmetrical and form right and left mates which cooperate as a pair to form the lower lid support member 5. The stamped grooves 20 and 21 of each of the matched stampings 15 and 16 cooperate to form a guideway for the pin 11. The pin 11 is held against rattling within the grooves 20, 21 by the plunger 13 and coil spring 14 which is held under load within the pin 11 by the plunger 13.

The operation of the lid is as follows: When the lid 1 is lowered, support member 4 is telescoped within support member 5 and the pin 11 is positioned adjacent the lower end of the groove 20 as shown in Figs. 2 and 3. When the lid is raised, member 4 slides outwardly of member 5 and the pin 11 travels upwardly in the groove 20 and then into groove 21 where it is directed by cam surface 25 into notch 26 which arrests upward movement of member 4 and the lid. Upon slight lowering of the lid, pin 11 strikes cam surface 27 which directs the pin into notch 28 in the island 22. In this position the lid is raised and latched.

To lower the lid, the lid is first raised slightly whereupon the pin 11 strikes cam surface 29 which deflects it into notch 30 which arrests upward movement of the lid. The lid is then lowered which causes the pin to travel downwardly to the left of the island 22 where it strikes cam surface 31 and is deflected to the right and back into groove 20, then downwardly to the position shown in Fig. 2 at which time the lid is completely closed.

The travel of the pin during the raising, latching, unlatching and lowering of the lid is indicated by the arrows in Fig. 6.

I claim:

1. A lid support comprising inner and outer telescoped members having their outer ends adapted to be pivotally secured to the lid and a

support therefor, the outer of said telescopic lid members comprising a matched pair of symmetrical metal stampings provided with matched stamped grooves which cooperate to form a guideway, a pin slidably held in a transverse slot in the inner telescopic member and adapted to travel in the guideway formed by the said grooves as the lid is raised and lowered, and cooperating cam surfaces and stops formed in said matched symmetrical members along the said guideway arranged to coact with said pin whereby the lid can be automatically latched upon raising the same and automatically unlatched preparatory to lowering the same.

2. A lid support comprising inner and outer telescoped members having their outer ends adapted for pivotal securement to lid and support members, the inner telescopic member being provided with a transverse slot near its inner end,

the outer telescopic member comprising a pair of matched symmetrical members having a guideway stamped therein in the form of a continuous groove, and cooperating cam surfaces and stops formed in said matched symmetrical members along the said guideway, a pin slidably held in said transverse slot of the inner lid support member and adapted to travel in the said groove as the lid is raised and lowered whereby the said cam surfaces and stops coact with the pin upon raising the lid to automatically latch the inner and outer lid supporting members in extended raised position and coact preparatory to lowering the lid to automatically unlatch the inner and outer lid supporting members to permit sliding of the inner member into the outer member during the lowering of the lid.

GEORGE N. HARDEN.
